STORAGE UNIT FOR BOXES HAVING OPEN TOPS

David Meade Peebles, 325 Marcy Ave.,
Oxon Hill, Md. 20021Filed Apr. 27, 1965, Ser. No. 451,213
2 Claims. (Cl. 312—270)

This invention relates to improvements in storage devices.

Storage units are available on the market which consist of sturdy steel frames having spaced shelves and storage boxes in various sizes which fit the shelves. The storage boxes are customarily formed of fiberboard. These boxes usually have slip covers or lids which are spaced only a slight distance from the next-uppermost shelf when the boxes are in place on the shelves with the lids upon them. Consequently, it is necessary to bodily remove each box from its shelf and to bodily remove the lid or cover of each box in order to gain access to the interior thereof. This is annoying and time-consuming and detracts from the utility of the storage unit. Nevertheless, the lids are necessary in many instances where it is required to keep dust and the like out of the boxes and to protect the contents thereof from soiling.

It is the object of this invention to provide a storage unit in which storage shelves and boxes are employed, but in which there is no necessity for providing covers or lids on the boxes because of the provision of novel means constituting a part of the shelving for sealing the open tops of the boxes while they are in place upon the shelves.

More specifically, according to the invention, the storage unit embodies a number of storage compartments, each adapted to receive an open top box or boxes, together with yielding surface means on either the top or bottom of the compartment allowing the compartment to receive the box snugly and to seal the same and yet allowing the ready removal thereof when necessary.

Another object is to provide an improved storage unit which is dust-proof, rugged and durable, and economical to manufacture.

Other objects and advantages of the invention will become apparent during the course of the following detailed description.

In the accompanying drawings forming a part of this application and in which like numerals are employed to designate like parts throughout the same,

FIGURE 1 is a perspective view of a storage unit embodying the invention;

FIGURE 2 is an enlarged fragmentary vertical section taken on line 2—2 of FIGURE 1 and depicting the placement of one box in a compartment of the unit, a second box being shown in the covered and sealed position;

FIGURE 3 is a view similar to FIGURE 2 showing a modification of the invention;

FIGURE 4 is a fragmentary view similar to FIGURE 2 showing another modification; and

FIGURE 5 is a view similar to FIGURE 4 showing still another modification.

In the drawings, wherein for the purpose of illustration are shown preferred embodiments of the invention, attention is directed first to FIGURES 1 and 2, wherein the numeral 10 designates a preferably steel storage frame or rack in its entirety, which is conventional in construction. The rack 10 comprises any preferred number of vertically spaced horizontal shelves 11, rigidly secured to the vertical members 12 of the rack in any preferred or conventional manner. The several shelves 11 may be equidistantly spaced vertically or they may be variably spaced, if preferred.

The several compartments 13 of the storage rack formed by the spaced shelves 11 are adapted to receive removably a desired number of open top rectangular storage boxes

2

14, 15, 16 and 17 whose widths or sizes may vary from compartment-to-compartment, as shown in FIGURE 1, or whose size may be standard throughout the storage unit, if preferred. These boxes may be formed of fiberboard or any other durable lightweight material including plastic or sheet metal. Each box is preferably provided with a grasping element 18 on its forward side to facilitate removal forwardly from the compartment which holds it. As shown in the drawings, the boxes are of a height to extend substantially from the top of one shelf to the bottom of the next-uppermost shelf of the storage rack. In effect, as shown in the drawings, the several boxes while in the storage position occupy substantially the entire volume of the rack or unit, so that no space is wasted.

With continued reference to FIGURES 1 and 2, means are provided on the rack 10 in association with the shelves 11 to seal the open tops of the storage boxes 14, etc. during use so that the same will be substantially dust-proof and also secure upon the shelves. As shown in FIGURE 2, this means may comprise an upwardly yielding surface 19 or plate on the bottom of each shelf 11, having bonded thereto a backing pad 20 of compressible material such as sponge rubber, rubber-like material, or certain well-known foam plastics. In any event, the element 20 is yielding and permits the necessary degree of upward displacement of the surface or plate 19 when one or more of the storage boxes is to be introduced into a compartment 13 between adjacent shelves of the rack. Prior to such introduction, in the manner depicted in FIGURE 2, the actual space between each plate 19 and the underlying shelf 11 is slightly less than the height of the box 14, etc. When the plate 19 yields upwardly due to introduction of the box into the chamber 13, the box will slide snugly into the compartment and the plate 19 will cover and effectively seal the top of the box, as shown clearly in the lower portion of FIGURE 2. To further facilitate the easy entry of each box into its compartment, the forward edge of the yielding plate 19 is provided with a smoothly rounded lip 21.

The underlying shelf 11 is substantially rigid or unyielding, whereas each plate 19 may yield upwardly to the extent permitted by the small gap 22 between it and the downturned flanges of the adjacent shelf 11. The extent of movement of the plate 19 is sufficient to allow complete entry of the box 14 into the compartment 13. The downturned flanges on the shelves 11, FIGURE 2, constitute positive stop elements to limit upward movement of the plates 19 when the boxes 14 are fully inserted into their compartments. The yielding pressure of the pad 20 under compression is adequate to form a firm and completely dust-proof seal with the open top of the box 14 after the box is completely inserted into the compartment 13, as illustrated by the lower portion of FIGURE 2. The plate 19 is preferably cemented to the bottom of the pad 20 and the latter may be adhesively secured to the overlying shelf 11. Other means of attachment may be employed, if desired. The arrangement does not interfere with the easy removal of the storage boxes from the rack.

The construction is particularly useful in connection with the storage of clothing, blankets and the like which it is desired to protect from dust, moisture and moths. Valuable paper documents are also protected by the sealing arrangement from the effects of moisture, mildew and the like. It is thought that the storage unit constructed according to FIGURES 1 and 2 will have a wide range of utility and that the various uses of the device will be apparent to those skilled in the art.

FIGURE 3 of the drawings shows a slight modification wherein a storage rack 10' includes spaced compartments 13' corresponding to the compartments 13. The identical

storage boxes 14, 15, etc., are utilized. The structure differs from the first-described embodiment only in that the bottom surface 23 or wall of each compartment 13' is the yielding surface rather than the top surface, as in the prior embodiment. In FIGURE 3, the bottom member 24 of each shelf is fixed or rigid and the plate or member defining the surface 23 is adapted to yield downwardly, as shown in FIGURE 3, when the open top storage box 14 is introduced into the compartment 13'. Each plate 23 has a downturned rounded lip 25 at the mouth of the compartment 13' to ease the entry of the box 14 into the compartment. Each plate 23 is adhesively secured to an underlying resilient compressible pad 26 which may be identical to the previously-described pad 20. Each pad 26 is supported by the fixed plate or member 24 beneath it. As in the previously-described embodiment, the compartment 13' is initially and normally slightly shallower than the height of the box 14 so that the top of the box will be firmly sealed after the compartment expands to receive the box, as shown at the lower portion of FIGURE 3. In all other respects, the construction and mode of operation in FIGURE 3 is identical to the first-described embodiment.

FIGURE 4 illustrates a further modification wherein the top wall of each storage compartment 27 of the multiple compartment unit is formed by a compressible pad 28 which is cemented to the adjacent fixed shelf 29. The bottom surface of each pad 28 carries an integral skin or layer 30 of cured plastic or the like which is smooth and relatively stiff and adapted to form a good sealing surface for engagement with the top of the storage box. The surface 30 readily yields upwardly when the box is introduced into the compartment 27 and like the other forms of the invention, the pad 28 presses the surface 30 to firm sealing contact with the upper edges of the box 14 around the entire margin of the box to protect the contents thereof.

FIGURE 5 shows still another modification, wherein the box sealing surface of each storage compartment 31 consists of a plate 32 urged downwardly by springs 33 which have their upper ends engaging the fixed shelves 34 of the unit. The plate 32 has the previously-described rounded lip 35 and the plate 32 may shift upwardly as the box 14 enters the compartment 31 and the springs will hold the plate in sealing contact with the open top of the box as in the other embodiments.

The constructions shown in FIGURES 4 and 5 may also be employed at the bottoms of the storage compartments rather than at the tops, if preferred. Various other

yielding surface arrangements in addition to those shown in the drawings may be employed including various types of springs and various forms of compressible resilient pads.

It is to be understood that the forms of the invention herewith shown and described are to be taken as preferred examples of the same, and that various changes in the shape, size and arrangement of parts may be resorted to, without departing from the spirit of the invention or scope of the subjoined claims.

The invention having thus been described, what is claimed is:

1. A storage unit comprising vertical corner members constituting legs, horizontal vertically spaced substantially rigid shelves secured rigidly to the legs and forming there-with a multiple compartment shelf-type storage structure, resilient compressible pads secured to the bottom faces of the shelves and substantially coextensive therewith and projecting below the bottoms of the shelves when in an uncompressed condition, flat substantially rigid plates secured to the bottom faces of said compressible pads and being vertically movable relative to the shelves when the pads are compressed upwardly, downturned flanges on the longitudinal edges of the shelves engageable with said plates to positively limit upward displacement thereof, and a plurality of open top storage boxes adapted to slidably enter said compartments between adjacent shelves and said plates and being of a vertical height to cause compression of said pads upwardly and upward displacement of said plates upon entry into the compartments between the shelves, said plates completely covering the open tops of said boxes and firmly sealing the open tops.
2. The invention as defined by claim 1, wherein said pads are formed of foamed rubber-like material and adhesively secured to the bottom faces of the shelves, said plates adhesively secured to the bottom faces of the pads.
